UNITED STATES PATENT OFFICE

FRANK R. HOUSE, OF BALDWIN HARBOR, NEW YORK, ASSIGNOR, BY MESNE ASSIGNMENTS, TO SPERRY GYROSCOPE COMPANY, INC., A CORPORATION OF NEW YORK

SEARCHLIGHT-VENTILATING MEANS

Application filed September 3, 1924. Serial No. 735,540.

This invention relates to searchlights and more particularly to a ventilation system for the same. The invention has for its principal object the provision of an effective system of ventilation which shall provide fresh, cool, unused air in the desired places for carrying away a maximum quantity of heat without disturbing the arc.

5

Further this invention has for its object 10 the provision of what I term a parallel ventilation system, the term "parallel" being used in its electrical sense, i. e. a plurality of streams of fresh, cool, unused air are drawn upwardly through one or more inlets in the 15 drum and so guided that each stream comes into direct contact with the heated portion of areas which it is desired to cool, and said streams are then united to form a single outlet stream. It is to be understood that 20 the term "parallel" is used in this sense throughout the specification and claims. Thus, for example, I may direct parallel streams of air upwardly through the drum, one stream in contact with the front door 25 or window to carry off the fumes which might otherwise deposit thereon, a second parallel stream for carrying off the heat generated at the arc and a third parallel stream of air for cooling the surfaces of the reflector.

30 A further object of the invention is the provision of means for carrying off the heat generated adjacent the arc, as described hereinbefore, in such manner that disturbance of the arc by the upward flow of air will 35 be prevented.

40 A further object of the invention is the provision of cooling means, as hereinbefore described, which shall be effective to cool also the control box and the various lamp controlling mechanisms therein.

Other objects and advantages of this invention will be in part obvious and in part specifically pointed out in the following detailed description of the invention.

45 In the accompanying drawings

Fig. 1 is a front view of a large searchlight, which, in the case shown, is the Sperry 60" high intensity searchlight.

50 Fig. 2 is a side view thereof, showing the general positioning of the air inlets.

Fig. 3 is a detail view showing the eccentric mounting of the reflector to provide an eccentric air opening whereby uniform distribution of air is obtained.

Fig. 4 is a vertical section through the lamp 55 of Figs. 1 and 2.

Fig. 5 is a front view, partially sectioned vertically and with parts broken away, showing my invention applied to a smaller lamp, which, in the case shown, is the 18" Sperry 60 searchlight.

Fig. 6 is a vertical section through the searchlight shown in Fig. 5.

Referring to the drawings, I have shown 65 my invention applied to two different types of searchlights, Figs. 1 to 4 disclosing the invention applied to a Sperry 60" searchlight, while Figs. 5 and 6 show the same principles applied to a smaller searchlight, such as the 18" type.

70 Referring to Figs. 1 to 4 inclusive, there is shown a searchlight drum 10 having horizontal trunnions 11 journaled for oscillation in bearings 12 at the upper end of a bracket 13 mounted for rotation in azimuth on a base 75 14. Within the drum adjacent the rear wall thereof, there is mounted a reflector 15 in suitable clamps 16 on an inwardly extending flange or rim 17 on the drum. The ventilating passage 20, communicating with the drum 80 at a plurality of points 21, 22, 23, terminates in a suction pump or fan 25 which may be driven by a motor 24. When the motor 24 is operating, air will be sucked out of the drum through apertures 21, 22, 23 into the 85 passage 20 and thence expelled.

85 The inlet passages whereby air enters the drum may comprise the large openings 26 (see Fig. 4) in the bottom of the drum and side openings 27, 28 at each side thereof.

90 The air inlets 26, 27, 28 and the outlets 21, 22, 23 are so positioned as to cool definite portions of the lamp structure with a minimum disturbance of the arc. The air inlets 26 are covered by a baffle plate 30 so that the arc is 95 not disturbed by the direct inrush of cool air and the air is distributed over the bottom of the drum. After the air emerges from the baffle plate 30, it is separated and drawn upwardly toward the three openings 21, 22, 23 100

in three streams of air by the suction of pump 25. It will be noted that opening 21 is closely adjacent the front window so that one stream of air will flow upwardly in a plane substantially parallel to and in contact with the front window to keep said window free from fumes and other deposits which might otherwise obscure it. The second opening 22 is placed substantially over the arc so that a second stream of air will flow upwardly in a plane substantially parallel to the plane of the first stream of air and will carry off the heat generated in the immediate vicinity of the arc. A third stream of air will be sucked upwardly 15 through opening 23 to cool the reflector, the air first passing through an opening 32 formed between the reflector 15 and its supporting flange 17. The three streams of air are thus connected in parallel to the common inlet and common outlet.

In order that the upward rush of air shall not disturb the arc, additional openings 27, 28, are provided in the drum at the sides thereof so that a substantial portion of the inflowing air shall pass through said side openings and thus reduce the amount of suction effective to draw air upwardly from the openings 26 and so prevent disturbance of the arc.

Since the suction upon the stream of air 30 adapted to cool the reflector is greatest in the vicinity of opening 23, there would ordinarily be a tendency for the air to rush immediately toward the upper portion of opening 32 between the upper edge of reflector 15 and 35 the upper portion of flange 17. To obviate this condition, which would ordinarily result in cooling only the upper portion of the reflector, I form the flange 17 eccentrically to provide a crescent shaped opening 32 larger at the bottom than adjacent the top, as shown in Fig. 3; in other words, the area of opening 32 increases the greater its distance from the outlet. In this manner the greater area of opening 32 adjacent the bottom will compensate for the greater suction 40 adjacent the top of the reflector so that a substantially uniform amount of cooling air will be drawn in at all points along the periphery of the reflector.

It will be seen from Fig. 4 that the curvature of the rear wall 40 of the drum 10, upon which the reflector 15 is resiliently mounted, as shown at 41, is formed with a lesser degree 45 of curvature than the reflector to provide a contracted opening 42 between the center of the reflector and the rear wall 40. Said contracted portion 42 will cause a more rapid flow of air to pass the center portion of the reflector than along the edges and will thus 50 compensate for the tendency of the air to pass upwardly around the outer peripheral portion of the reflector in its effort to reach the outlet opening 23.

From the above description, it will be seen 55 that I have accomplished the following ob-

jects, namely; I have provided for definite streams of air for cooling different parts of the lamp; secondly, the streams are composed of fresh, cool, unused air; thirdly, means are provided for preventing the upward flow of air from disturbing the arc; fourthly, means are provided for insuring cooling of the lower portion of the reflector to the same extent as the upper portion thereof; fifthly, means are provided for cooling the central portion of the reflector to substantially the same extent as the peripheral portion thereof.

In the type of lamp described in Figs. 1 to 4, a control box 45 combining the control mechanism is shown mounted upon the side 80 of the drum.

Certain of the principles hereinbefore outlined are shown applied to a different form of searchlight in Figs. 5 and 6. In this form of searchlight, the driving motor 24' and the 85 suction pump 25' are shown mounted in a hood 50 on the upper surfaces of the drum. Similarly, openings 26', 21', 22', 23', corresponding to the same numerals unprimed in Figs. 1 to 4 are provided and function in a 90 similar manner.

The control box 45' is, in this instance, mounted directly above the opening 26' so that the controlling mechanism contained therin is cooled by the inflow of air through 95 said opening. A crescent shaped opening 32' is again provided between the reflector 15' and the flange 17' for the same reasons set forth in connection with the Figs. 1 to 4 device. In this form of lamp, the side openings 27, 28 may, if desired, be omitted because the disturbing influence of the upward flow of air on the arc would not be so great in this type of lamp which, as shown, is a Sperry 18" lamp and may be a 12" or 24" lamp.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In combination, a searchlight comprising a drum, a front window, a reflector, said drum having air inlet means adjacent the bottom and a plurality of air outlets adjacent the top, suction means connected to said air outlets, said outlets being positioned adjacent said front window, above the arc, and adjacent the reflector respectively whereby a plu-

rality of streams of unused air are caused to travel upwardly through said drum from said inlet means.

2. In combination, a searchlight comprising a drum, a front window, a reflector, said drum having air inlet means adjacent the bottom and a plurality of air outlets adjacent the top, suction means connected to said air outlets, said outlets being positioned adjacent said front window, above the arc, and adjacent the reflector respectively whereby a plurality of streams of unused air are caused to travel upwardly through said drum from said inlet means, said drum having a plurality of air inlets at the sides thereof to prevent disturbance of the arc by said upwardly traveling streams of air.

3. In a searchlight comprising a drum having air inlet means adjacent the bottom thereof and an air outlet adjacent the top thereof, suction means for drawing air out of said outlet and causing a stream of air to travel upwardly through said drum for carrying off the heat generated by the arc, said drum having a plurality of air inlets at the sides thereof for preventing disturbance of the arc by said stream of air.

4. In a searchlight, a drum, a reflector mounted in said drum in spaced relation to the back thereof, and means for cooling said reflector comprising a peripheral air inlet surrounding the edge of said reflector, said drum having an air outlet adjacent the top thereof at the rear of the reflector, and suction means connected to said outlet whereby an unused stream of air is caused to travel upwardly over the rear surface of said reflector.

5. In a searchlight, a drum, a reflector mounted in said drum in spaced relation to the back thereof, and means for cooling said reflector comprising a peripheral air inlet surrounding the edge of said reflector, said drum having an air outlet adjacent the top thereof at the rear of the reflector, and suction means connected to said outlet whereby an unused stream of air is caused to travel upwardly over the rear surface of said reflector, said air inlet being formed to increase in size in proportion to its distance from said outlet.

6. In a searchlight, a drum, a reflector mounted in said drum, and means for cooling said reflector comprising a peripheral air inlet surrounding said reflector, said drum having an air outlet adjacent the top thereof, suction means connected to said outlet whereby an unused stream of air is caused to travel upwardly over the surface of said reflector, and means for compensating for the tendency of the air to enter mainly that portion of the inlet in the vicinity of the air outlet.

7. In a searchlight, a drum, a reflector mounted in said drum, and means for cooling said reflector comprising a peripheral air

inlet surrounding said reflector, said drum having an air outlet adjacent the top thereof, suction means connected to said outlet whereby an unused stream of air is caused to travel upwardly over the surface of said reflector, and means for compensating for the tendency of the air to pass upwardly mainly adjacent the periphery of said reflector.

8. In a searchlight, a drum, a reflector mounted in said drum, and means for cooling said reflector comprising a peripheral air inlet surrounding said reflector, said drum having an air outlet adjacent the top thereof, suction means connected to said outlet whereby an unused stream of air is caused to travel upwardly over the surface of said reflector, and means for compensating for the tendency of the air to pass upwardly mainly adjacent the periphery of said reflector, said means consisting in forming a passage between said reflector and said drum, said passage being gradually reduced in area toward the center of the reflector.

9. In a searchlight, a drum, a reflector mounted in said drum, and means for cooling said reflector comprising a peripheral air inlet surrounding said reflector, said drum having an air outlet adjacent the top thereof, suction means connected to said outlet whereby an unused stream of air is caused to travel upwardly over the surface of said reflector, means for compensating for the tendency of the air to enter mainly that portion of the inlet in the vicinity of the air outlet, and means for compensating for the tendency of the air to pass upwardly mainly adjacent the periphery of said reflector.

In testimony whereof I have affixed my signature.
